Fig. 4

Fig. 5

Fig. 6

Fig. 7

FIG. 1 is a perspective view of a cigarette lighter showing my new design:

FIG. 2 is a right side elevation thereof;

FIG. 3 is a rear elevation thereof;

FIG. 4 is a top plan view thereof;

FIG. 5 is a bottom plan view thereof;

FIG. 6 is a front elevation thereof; and

FIG. 7 is a left side elevation thereof.

I claim:

The ornamental design for a cigarette lighter, substantially as shown.
